UNITED STATES PATENT OFFICE.

GEORGE A. FARRAH, OF SPENCER, WEST VIRGINIA.

VALVE-OPENING DEVICE.

984,084.

Specification of Letters Patent. Patented Feb. 14, 1911.

Application filed December 17, 1909. Serial No. 533,623.

To all whom it may concern:

Be it known that I, GEORGE A. FARRAH, a citizen of the United States, residing at Spencer, in the county of Roane and State of West Virginia, have invented a new and useful Valve-Opening Device, of which the following is a specification.

This invention relates to a device for opening the standing valve of oil and other deep wells, and also the valve of the pump piston, when said valves have become set or stuck, or when it is desired to empty the well tubing.

In deep well pumping it frequently happens that by sand and other matter collecting on the valve seat, the valve is prevented from working properly. This difficulty can be readily remedied by opening the valve, and letting the oil or other fluid run back into the well to wash away the accumulation on the valve seat. It also becomes necessary at times to pull the tubing out of the well, and when this is done it is desirable to first empty the oil or other fluid contained in the tubing back into the well, in order to prevent the same from being wasted. When ordinary valves are used, this cannot be done and the oil or other fluid is wasted, amounting sometimes to several barrels. However, by the use of my invention, the valves can be readily opened to let the oil or other fluid run back into the well, and this may also be done if it is desired to flood the well, which is usually done by drilling a hole in the tubing at the bottom of the well, this necessitating a shut down of the pump until the oil or other fluid leaks out.

The invention has for its object to provide a device for the purpose stated which is simple in structure, easily operated, and efficient and reliable in action.

With this object in view, the invention consists in a novel construction and arrangement of parts to be hereinafter described and claimed, reference being had to the drawing hereto annexed in which,

Figure 1 is an elevation of a standing valve and a pump piston valve showing the application of the invention. Fig. 2 is a central vertical section of the parts shown in Fig. 1. Fig. 3 is a view similar to Fig. 2 showing the parts in another position.

Referring to the drawing, 5 denotes the casing of the standing valve located at the bottom of the well tubing, the latter not being shown. The valve body is provided

with a packing leather 6 whereby it is held at a fluid tight fit within the well tubing. The valve casing is tubular, and contains a seat 7 for a ball valve 8, the upper end of the casing being provided with a cage 9 enclosing the ball. This cage screws on the upper end of the valve casing, and has an interior shoulder 10 engageable with one side of an annular flange 11 on the valve seat 7, said seat being in the form of a sleeve fitting in the bore of the casing 5, and having the other side of the flange in engagement with the upper end of the casing, against which it is held by the shoulder 10.

Rising from the upper end of the valve cage 9, and formed integral therewith, is a tube 12, in which is slidably mounted a tubular stem 13 having at its lower end an enlargement 14 engageable with a seat made in the lower end of the tube 12.

On the stem 13, above the upper end of the tube 12, is screwed a sleeve 15 having a depending tubular portion 16 loosely fitting on the tube 12 so that it may slide up and down thereon. Around the stem 13 is coiled a spring 17 engageable at one end with a shoulder 17^a in the bore of the tube 12, and at the opposite end with the sleeve 15. The tension of the spring 17 may be adjusted by screwing the sleeve 15 up or down on the stem 13.

The stem 13 projects from the upper end of the sleeve 15, and on said projecting-end is screwed a coupling head 18, between which head and said end of the sleeve is clamped a ring 19 formed with a downwardly projecting finger 20, having its lower end inturned so that it may engage the ball valve 8, and push it off its seat 7. The finger 20 lies in a groove made in the outer surface of the tubular portion 16 of the sleeve 15, and it extends through one of the side openings of the cage 9. Into the upper end of the coupling head 18 is screwed a tubular stem 21 which is for a purpose to be presently described. At 22 is indicated the pump piston, the same being tubular, and containing a seat 23 for a ball valve 24. The stem 21 is in axial alinement with the bore of the piston, and is adapted to enter said bore when said piston is lowered sufficiently, so that it may engage the ball valve 24 and lift the same off its seat. The length of the stem 21 is such that it does not unseat the valve 24 during the normal working stroke of the piston.

To unseat the ball valve 8, the piston 22 is lowered until the stem 21 enters the same, and lifts the valve 24 off its seat, the valve being elevated until it engages the upper 5 end of its cage. A continued downward movement of the piston, over the rod 21, slides the sleeve 15 downwardly on the tube 12, this downward movement being continued until the finger 20 engages the ball 10 valve 8, and pushes the same sidewise off its seat, so that now both valves are open. The spring 17 is compressed when the finger moves downwardly to move the ball valve 8 as stated, and it therefore serves to automatically 15 slide the spring finger upwardly and release said valve when the stem 21 is released by the piston, whereupon the valve drops back to its seat 7. The valve 24 drops back to its seat when the piston 22 is 20 turned to its working position.

By the device herein described, the valve can be readily opened to permit the well tubing to empty, the device is simple in structure, and can be easily operated, and it 25 therefore effectually serves the purpose for which it is designed.

What is claimed is:—

1. In a well, the combination with the standing valve; of a tube rising from said 30 valve, a sleeve slidably mounted on the tube, a valve opening device carried by the sleeve,

and engageable with the valve proper when the sleeve is lowered, means for lowering the sleeve, and yielding means opposing said movement of the sleeve. 35

2. In a well, the combination with the standing valve; of a tube rising from the cage thereof, a stem loosely mounted in the tube, a sleeve carried by the stem and slidably mounted on the aforesaid tube, a valve opening device carried by the sleeve, and engageable with the valve proper when said sleeve is lowered, and means for lowering the sleeve. 40

3. In a well, the combination with the standing valve; of a tube rising from the cage thereof, a stem slidably mounted in the tube, a sleeve carried by the stem, and slidably mounted on the aforesaid tube, a coupling head mounted on the stem, a ring held between the coupling head and the sleeve, and a valve opening device carried by the ring, and adapted to engage the valve proper to unseat the same. 45

In testimony that I claim the foregoing 55 as my own, I have hereto affixed my signature in the presence of two witnesses.

GEORGE A. FARAH.
